[57] CLAIM

The ornamental design for a stuffed toy armadillo, as shown and described.

DESCRIPTION

FIG. 1 is a left side view of a stuffed toy armadillo showing my new design, it being noted that a right side view would be a mirror image of FIG. 1;

FIG. 2 is a top view of the stuffed toy armadillo of FIG. 1;

FIG. 3 is a bottom view of the stuffed toy armadillo of FIG. 1;

FIG. 4 is a front view of the stuffed toy armadillo of FIG. 1; and

FIG. 5 is a rear view of the stuffed toy armadillo of FIG. 1.

FIG 6-4
